DESIGN FOR A FLY SWATTER

Adolph F. Shafter, Decatur, Ill., assignor to U. S.
Manufacturing Corporation, Decatur, Ill.

Application March 6, 1934, Serial No. 50,954

Term of patent 14 years

To all whom it may concern:

Be it known that I, ADOLPH F. SHAFTER, a citizen of the United States and a resident of Decatur, county of Macon, and State of Illinois, have invented a new, original, and ornamental Design for a Fly Swatter, of which the following is a specification, reference being had to the accompanying drawing, forming part thereof.

In the drawing—

Fig. 1 is a plan view of a fly swatter, showing my new design;

Fig. 2 is a side elevation; and

Fig. 3 is a sectional view of the lower blade portion of the fly swatter.

I claim:

The ornamental design for a fly swatter as shown.

ADOLPH F. SHAFTER.
